[57] CLAIM

The ornamental design for an optical character reader
for electronic computers, as shown.

DESCRIPTION

FIG. 1 is a top, front and right side perspective view of
an optical character reader for electronic computers
showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a bottom plan view thereof.

FIG. 1

FIG. 2

FIG. 3

FIG. 4

FIG. 5

FIG. 6

FIG. 7
